TRACTOR CAB

Oscar Stanley Williams, Arlington, Ind. 46104

Filed Jan. 5, 1972, Ser. No. 215,699

Term of patent 14 years

Int. Cl. D12—09

U.S. Cl. D40—5

Fig. 1.

Fig. 2.

Fig. 6.

Fig. 7.

Fig. 8.

Fig. 3.

FIG. 4.

FIG. 1 is a perspective view of the tractor cab applied to a tractor showing my new design;

FIG. 2 is a front elevational view thereof;

FIG. 3 is a rear elevational view;

FIG. 4 is a side elevational view opposite from that shown in FIG. 1;

FIG. 5 is a top plan view;

FIG. 6 is a detail cross section on the line 6—6 in FIG. 4;

FIG. 7 is a detail cross section on the line 7—7 in FIG. 4; and

FIG. 8 is a detail cross section on the line 8—8 in FIG. 4.

The dominant part of the invention resides in the portions shown in full lines in the drawings.

I claim:

The ornamental design for a tractor cab, substantially as shown and described.
